Primary Examiner — Shawn T Gingrich*Assistant Examiner* — Bryan N. Melvin(74) *Attorney, Agent, or Firm* — Kolitch Romano Dascenzo Gates LLC(57) **CLAIM**

We claim the ornamental design for a switch plate, as shown and described.

DESCRIPTION

FIG. 1 is a front view of a switch plate showing the design. FIG. 2 is a side elevation view thereof, with the opposite side view being the mirror image thereof.

FIG. 3 is an isometric view thereof; and,

FIG. 4 is a top plan view thereof.

The back of the switch plate forms no part of the claimed design.
